UNITED STATES PATENT OFFICE

2,009,224

FURNITURE

Cecil W. Farrar, Buffalo, N. Y.

Application April 1, 1932, Serial No. 602,413

8 Claims. (Cl. 45—38)

My invention relates to furniture, and more particularly to a sheet metal furniture structure.

An object of my invention is to provide a new article of manufacture comprising a dressing table including a lavatory.

Another object is to provide a novel lavatory.

Another object is to provide novel means for joining together the parts of metal furniture structures.

10 The invention consists in the combination and improved construction of parts, to be more fully described hereinafter and the novelty of which will be particularly pointed out and distinctly claimed.

15 In the accompanying drawings, to be taken as a part of this specification, I have fully and clearly illustrated a preferred embodiment of my invention, in which drawings—

Figure 1 is a view in perspective of the furniture 20 structure embodying my invention;

Fig. 2 is a top plan view of the structure of Fig. 1, partly in section, and with certain parts broken away to show the internal construction;

Fig. 3 is a detail vertical section on the line 25 3—3 of Fig. 2;

Fig. 4 is a detail vertical section on the line 4—4 of Fig. 2;

Fig. 5 is a vertical section on the line 5—5 of Fig. 2;

30 Fig. 6 is a top plan view of the basin member;

Fig. 7 is a view in front elevation of the basin member showing the hot and cold water inlet conduits and part of the supporting framework;

Fig. 8 is a view in end elevation of the basin 35 member;

Fig. 9 is an enlarged detail view in horizontal section on the line 9—9 of Fig. 5;

Fig. 10 is a view in vertical section on the line 40 10—10 of Fig. 2;

Fig. 11 is a detail horizontal sectional view on the line 11—11 of Fig. 5;

Fig. 12 is a detail view in vertical central section of the drain or outlet control valve with a modified operating mechanism therefor;

45 Fig. 13 is a detail view, partly in horizontal section, of the valve and mechanism of Fig. 12; and

Fig. 14 is a partial front elevation of the construction shown in Fig. 1, modified to include the waste valve operating mechanism shown in detail 50 in Figs. 12 and 13.

Referring to the drawings by characters of reference, 1 designates, generally, a furniture structure or combined lavatory and dressing table, which is preferably constructed of sheet metal and which comprises laterally positioned and

spaced cabinet supporting members 2, 3 with an intermediately supported basin or bowl member 4 behind which there is preferably a mirror 5. The basin supporting cabinet members 2, 3, are substantially identical, and a description of one will therefore suffice for both. Each cabinet member comprises a main casing and a supplemental superposed casing, the main casing having a bottom wall or plate 6, which at its forward edge is stepped downward and rearward, as at 7, terminating in a rearward flange 8 which is secured to front corner posts or legs 9. At its side and rear edges the wall 6 has depending flanges 10, 11 which are secured to the side and rear casing walls or plates 12, 12^a and 13, respectively, which depend below the flanges 10, 11 and have inwardly directed flanges 14, 15, respectively, in the plane of flange 8, and which flanges 14, 15 are secured to the front corner legs 9 and also to the rear corner posts or legs 16. The forward edges of the side 10 walls 12, 12^a are preferably of laterally and forwardly stepped form, as at 17, each wall terminating in a rearwardly directed flange, the flange of the outer side wall being designated 18 and of the inner side wall being designated 19. The 15 main casing has side wall liners or plates 20 which extend substantially parallel to the side walls and are aligned with the flanges 18, 19, see Fig. 11. Each of the liners has marginal flanges 21 directed toward its respective side wall, the bottom 20 flanges 21 being secured to the bottom plate 6, the rear edge flanges 21 being secured to the rear casing wall and the front edge flanges being bent to cooperate with the stepped front corners 17, as at 22 (see Fig. 11). Horizontal partitions or 25 shelves 23 may be inserted in the main casing and be secured to the side liners, as at 24. Fig. 11, by nuts and bolts, or the like. Above the topmost shelf, the casing preferably has a horizontal plate member 25 defining a drawer support, secured to the rear casing wall by a depending flange 26 and having longitudinal, upstanding side flanges 27 terminating in inwardly directed overhanging guide rails or flanges 28. The forward end of member 25 terminates in an upright flange 25^a 30 which defines the top cross-frame member of the door openings, of which flanges 18, 19 define the side members. Also at the forward end of the member 25 the flanges 28 are omitted to permit projection thereabove of the top surfaces of horizontally journaled guide rollers 29 secured to the flanges 27. The drawer, designated 30, has a bottom wall 31 which rides on the rollers 29 and has at its rear end a roller supporting bracket 32 having parallel depending bearing ears 33 through 35

which extends a shaft 34 having on its outer ends rollers 35 which fit between the supporting member 25 and the rails 28 (see Fig. 3). The top marginal liner flanges 21 are preferably substantially in the plane of member 25. The top marginal edges of the rear wall 13 and of the outside side wall 12 are each provided with a longitudinal upward open groove 36, preferably formed by bending the metal downward and upward in planes parallel to their respective walls, as in Fig. 4. The inside side wall 12^a has a similar groove 37 which extends from the front edge rearward for only a short distance, and therebeyond, the wall 12^a has a substantially horizontal inturned flange 38 set below the top edge of the groove 37. A top wall or closure member 39 which conforms to the plan outline of the casing, has a depending marginal flange along its outside side, its rear, and a portion of its inside side edges, as at 40, which is secured in the groove 36, 37. Above the flange 38 the member 39 has an undeturned or extending flange 41, which has spaced apertures there-through which overlie apertures in the flange 38, the aligned apertures being designated 42. The front edge of the top wall 39 is turned downward and then inward, as at 43, to form the front top cross-frame member. The opening to the shelves defined by the bottom wall 6 and elements 18, 19 and 25^a, is closable by a door or closure member 44 which is hinged, as at 45, to the outside flange 18. The supplemental casing, designated 46, is substantially similar to the top portion of the main casing above and including the support 25, similar parts being designated by the primes of the reference characters applied to like parts of the main casing. The casing 46 rests upon and is secured to the top wall 39 at the rear thereof such that the rear walls are substantially in a common plane.

Between the supporting members 2, 3 there is a supporting framework which is parallel to and adjacent the plane of the rear walls of the supporting members (see Figs. 5, 7 and 9). The framework comprises a top frame member 47, from the ends of which depend vertical side frame members 48, 49 which are joined by reinforcing cross-bars 50. The members 47, 48 and 49 are preferably angle-irons, each having one flange extending forwardly, as at 51, and having the other flanges 52 in a common vertical plane directed inward or toward each other. The vertical forwardly directed flanges 51 are bolted, as at 53, or otherwise secured to the outer faces of the inside side walls of the members 2, 3, and preferably to vertically extending angle-irons 54, or the like, within the cabinet members (see Fig. 9). The basin member 4 rests at its rear portion on the horizontal top frame member 47, and has lateral flanges 55 which are slotted or notched, as at 56, for register with the aligned apertures 42. The flanges 55 extend between the undeturned flanges 41 and the side wall flanges 38, and are tightly clamped thereto and therebetween by bolts 57, or the like, secured through the flange apertures. To prevent the side members 2, 3 from being pulled away from the basin member, brackets 58 are secured to the underside of the basin member and are bolted or otherwise secured, as at 59, to the inside side walls 12^a of the members 2, 3. At the front edge of member 4 there is a depending apron or wall member 60 which extends between the members 2, 3 and has rearwardly extending flanges 61 at its vertical side edges, which flanges are bolted or otherwise secured, as at 62, to the walls of the members 2, 3.

A reinforcing vertically extending angle-iron 63 may be positioned within each member 2, 3 and apertured for reception of the securing bolts 62. The lower edge portion of apron 60 extends rearward and upward, as at 64, to finish off the bottom edge of the apron. Interlocked with the portion 64 and extending between members 2, 3 is a closure plate 65 having side flanges 64^a and which is stepped downward and rearward and at its rear edge joins with a vertical back kick panel 10 or plate member 66 which joins the members 2, 3 and terminates in the plane of the cabinet bottom flanges 8, 14 and 15. Behind and adjacent the bottom of the member 66 there is a cross-frame member 65^a which is secured at its ends to 15 the casing members 2, 3. The member 66 is preferably removably secured in position by bolts 66^a, or the like, which clamp the member 66 to the member 65 and to the cross-frame 65^a, so that access may be had to certain piping concealed 20 thereby and to be described. The member 4 has a basin or bowl proper 67 substantially midway of the side edges thereof. At the rear of the basin bottom wall there is a drain outlet 68 provided with a control valve 69, preferably of the 25 pop-up type operated in the usual manner by a cam within the trapped drain pipe 70. The cam, as is customary, is carried by a rotatable shaft 71 which is oscillated by a plunger control rod 72 passed upward through an aperture 73 in the 30 member 4 and having on its top end a hand grip 74. The basin has an overflow outlet conduit 75 which leads into the pipe 70. A water inlet faucet or spout 76 overhangs the rear edge of the basin and rests on the member 4. The spout 76 is supplied by a pipe 77 extending upwardly through an aperture 78 in member 4, the pipe 77 being joined by a T connection or coupling 78 to the outlet ports of hot and cold water control valves 79. The valves 79 are controlled by rotatable hand grip members 40 80 secured on the front face of apron 60 and connected by torque rods 81 to the respective stems of valves 79.

The basin member 4 supports a mirror frame 82 which may be of any form or outline in elevation, but which has a straight lower horizontal cross-frame member 83. The frame is preferably hollow and of sheet metal, and is reinforced at its sides by vertical internal angle-irons 84 to 45 which are rigidly secured depending angle-irons 85, or the like, the irons 84, 85 cooperating to form a rectangle having its outer and forward sides formed by the angle-iron 85. The member 4 extends rearward beyond the frame member 47 and terminates in a depending flange 86 in the 50 plane of the cabinet rear walls 13, the flange preferably being secured to the members 2, 3. Through the member 4 adjacent its rear edge and between the flange 86 and the frame member 47, there are apertures 87 of right-angle outline which cooperate with and receive the angle-irons 85 so as to position the mirror on the member 4. The irons 85 extend downward through apertures 87 and are bolted or otherwise secured, as at 88, to the vertical frame members 48, 49 55 (see Fig. 5). The frame 82 contains and supports a mirror glass 89 having a backing member 90.

In Figs. 12 and 13 I have shown a modification of the valve operating mechanism, the use of 70 which is illustrated in Fig. 14. In this form the valve operating cam, designated 91, is oscillated by a lever arm 92. Connected to the arm 92, as at 92^a, there is a thrust member or wire 93 which is flexible and may be of steel, and which 75

is housed in a flexible guide tube 94. The tube 94 terminates at one end adjacent the valve and is supported therefrom or from a fixed support by an arm or bracket 95. The other end of the tube 94 is secured at and preferably to the inside face of the apron 60 by a clip, or the like, as at 96. The ends of the wire 93 project from the ends of the tube, and the free end of the wire is secured, as at 97, to a lever arm 98 rigid 10 with a rotatable shaft 99 which projects through a bearing sleeve 100 secured in an aperture through the casing, the aperture preferably being midway of the distance between the valve handles or grips 89. A control knob or handle 101 is secured on the external projecting end of shaft 99 for oscillation thereof to exert a pull or a push on the wire 93. In the full line position of the parts, see particularly Fig. 12, the valve is closed. If now the handle 101 is turned 20 counterclockwise of Fig. 12 to a vertical position, as shown in dotted lines, the arm 98 and wire 93 will be moved to the left, as shown in dotted lines, thus pulling on the wire and swinging the lever arm 92 and the cam 91 clockwise of Fig. 12 25 to lift the valve as indicated in dotted lines. My application, Serial No. 633,937 filed September 20, 1932, discloses a furniture construction including features of construction some of which are similar and others of which are alternative 30 in form to features of construction disclosed herein. Said application Serial No. 633,937 contains claims on subject matter disclosed but not claimed herein.

From the foregoing description, it will be obvious that I have provided a furniture structure which may be and preferably is fabricated in substantial entirety from metal and sheet metal elements, and which may readily be assembled and taken apart, as for shipment, the members 40 2, 3, 4 and the mirror structure each being separate units.

What I claim and desire to secure by Letters Patent of the United States is:—

1. A structure of the character described, comprising a hollow casing adapted to rest upon a floor and forming a supporting member, a supporting member spaced from said casing and adapted to rest upon the floor, and means rigidly connecting said supporting members comprising 45 a basin member positioned between said members and having water supply means and a drain outlet, and means rigidly securing said basin member to each of said supporting members.

2. A structure of the character described, comprising laterally spaced hollow casings adapted to rest upon a floor and forming supporting members, and means rigidly connecting said supporting members comprising a basin member positioned between said supporting members and having water supply means and a drain outlet, and means rigidly securing said basin member to each of said supporting members.

3. A structure of the character described, comprising a hollow casing having a side wall, a supporting member spaced from said wall, and means rigidly connecting said casing and supporting member comprising a basin member positioned

between said wall and said member and partly supported by said member, means joining one of the side edge portions of said basin member to said wall and rigidly securing it thereto, and means cooperating with said casing to provide support for said basin member at a distance from said wall.

4. A structure of the character described, comprising laterally spaced hollow casings having opposed side walls, and means rigidly connecting said casings comprising a framework extending between and secured to said walls, a basin member positioned between said casings and resting on said framework, and means joining the side edges of said basin member to said casings and anchoring said basin against an adjacent vertical wall of each of said casings.

5. A structure of the character described, comprising a hollow casing having a side wall and a top wall, a portion of said side wall terminating in a lateral flange in spaced underlying relation to said top wall, a basin member having an edge portion extending between said top wall and said flange and resting upon said flange, means clamping said edge portion between said flange and said top wall, means rigidly securing said basin member to said casing, and means cooperating with said casing to support said basin member.

6. A structure of the character described, comprising laterally spaced supporting cabinet members having substantially parallel opposed side walls, a basin member positioned between said cabinet members and having a substantially flat top wall and a bowl depending from and opening through said top wall, and supporting means secured to said walls adjacent the front and rear of said basin member, said basin member being secured to said supporting means with said top wall slightly below the top walls of said cabinet members, the side edges of said basin member 40 joining said cabinet members.

7. A structure of the character described, comprising laterally spaced supporting cabinet members having substantially parallel opposed side walls, a laterally directed flange adjacent the upper edge of each of said side walls, a basin member positioned between said cabinet members and having a substantially flat top wall and a bowl depending from and opening through said top wall, said basin member resting on said flanges, means securing said basin member to said flanges, and means securing said basin member and said cabinet members together.

8. A structure of the character described, comprising a supporting cabinet member, a supporting member positioned at the side of said cabinet member and spaced therefrom, the side wall of said cabinet member adjacent said supporting member terminating adjacent the top wall of said cabinet member in a substantially horizontal flange extending beneath said top wall, a basin member positioned between and carried by said supporting members and having a side edge portion thereof extending between said flange and said top wall, and means securing said top wall, 60 said flange and said edge portion tightly together.

CECIL W. FARRAR.
